UNITED STATES PATENT OFFICE.

EDWIN LANE, OF NEW YORK, N. Y., ASSIGNOR TO CAROLYN LAUNDRY, OF NEW YORK, N. Y., A CORPORATION OF NEW YORK.

LAUNDRY-HANDLING DEVICE.

Application filed November 16, 1925. Serial No. 69,556.

This invention relates to laundry handling devices, and in the present instance has particular application to a device whereby a number of garments or other pieces to 5 be laundered may be grouped in the device to identify the various articles or pieces belonging to a particular customer, thereby obviating confusion and loss and individual marking or identification.

10 Heretofore it has been the practice in laundries, to take a bundle or package of pieces or articles of a particular customer, and to group or string the same upon a flexible device such as a chain or rope, by 15 running the chain, for example, through an opening, such as a sleeve or the like, of a garment, or by tying flat pieces, such as towels, about the chain and then connecting the loose ends of the chain by a safety pin 20 or other fastener so as to form a closed loop upon which the articles were hung. At the safety pin end of the chain it has been the practice to swivel or attach a small tag bearing an identifying character, such 25 as a number, so that the articles or pieces strung upon the chain could be identified as belonging to a certain customer. The articles or pieces so strung upon the closed loop or end passed through the washing or 30 cleaning operation. But there are certain disadvantages incident to this method, and the device employed, for it has been found that under the stress of the washing operation there is a tendency of the swivel tag 35 or check or identifying chain to thrash about and hammer or beat against the fabric being laundered and thereby tearing or cutting the same.

Furthermore, the identifying tag so used 40 is usually in the form of a simple metal disk having an identifying character thereon, so that in the sorting of the laundry, after the washing operation, there is a liability of confusion in the handling of the 45 checks or tags, thus resulting in mistakes in the distribution of the laundered pieces of different customers.

To obviate these objections it is my purpose to provide a laundry handling device 50 in the nature of a flexible member such as a chain, wherein the identifying tag, instead of being linked or swivelled at the loose end of the chain with or adjacent to the fastening device, such as a safety pin, 55 is made to form an integral part of the

chain, or, in other words, to constitute a link thereof, the tag being located at or forming a link distant from the ends of the chain, or near the center of the latter, or near the end, but forming a part of the chain. 60

Furthermore, instead of employing a mere plain flat imperforate disk identified only by a number or the like, I formed this disk with an aperture or opening in the nature of a selected form of key way, so that 65 at the proper time, as in distributing the laundered pieces, a chain bearing a particular form of key way, may be threaded or fitted on a complementary key bar or rod, thereby insuring against confusion in the 70 assembling of the chains, for it will be apparent that as the operator removes the pieces from the chain, and hangs the latter on the key bar by means of the tag, only such tag as corresponds in its key way to a 75 particular key bar, can be threaded on the latter.

For example, if the tag and key bar each bear an identification character number 102, it will be impossible for the operator to 80 thread a tag 105 on the key bar along with chains bearing tags 102, consequently, there will be no liability afterwards in making the mistake of using a chain of the wrong 85 series in handling a particular customer's laundry.

My invention consists of the improved laundry handling device set forth in and falling within the scope of the appended 90 claims.

In the accompanying drawings:

Fig. 1 is a perspective view showing a number of the devices of the same series threaded upon a key bar.

Fig. 2 is a detailed view of one of the devices ready for use.

Fig. 3 shows the device connected in loop form with the plurality of laundered pieces properly placed thereon for the laundry operations.

Referring now to the accompanying drawings in detail wherein I have shown my device in the general form of a chain, the numerals 1 and 2 indicate two chain sections having relatively small links, these 105 chain sections being connected at adjacent ends through the medium of a flat metallic disk or tag 3, which forms in substance an enlarged link perforated approximately in the center of the chain. This tag 3 is pro- 110

vided with an identification number 4 and is also formed with an elongated aperture or opening 5, the walls of which are notched as shown in 6, this notched aperture constituting a key way, so that when not in use the device may be strung or threaded upon a key bar B having ribs or projections as at 6, complementary to or corresponding with the apertured opening in the tag. One end of the chain is preferably provided with a fastening device 7, in the present instance in the form of an ordinary safety pin, so that when the ends of the chain are connected by, for example, fastening the opposite end 8 of the flexible member or chain in the safety pin, a loop is formed as shown in Fig. 3, for the purpose of retaining the pieces to be laundered shown as C and which are strung thereon.

From the above description taken in connection with the accompanying drawings the construction and manner of employing my improved device will be readily understood.

For example, a particular customer may send in in one batch of laundry, articles of various kinds, such as towels, shirts, undergarments and the like. The chains when not in use are strung upon the key bar B as shown in Fig. 1. If this customer's batch is identified as number 102, for example, chains bearing a tag identified by number 102 are removed from a corresponding key bar and threaded through the openings of the sleeves of the shirts, for instance, or articles such as towels may be wrapped and knotted about the chain. The loose ends of the chain are then connected by means of the safety pin to form a loop as shown in Fig. 3. The articles in this shape go through the washing operation, and at the proper time the chain is unhooked and the article stripped therefrom. The chain is then placed back on the key bar ready for future use, and as the key way in the tag link of the chain will only fit a particular key bar it will be obvious that the chain cannot be placed upon the wrong key bar which would of course cause confusion in the sorting and identification of future batches of laundry should this misplacement occur.

The use of such a device is also intended to replace the expensive net bags in which it is also customary to wash certain laundry

pieces, as with my device not only are the articles properly secured for identification in washing, but the expense and annoyance and delay used in handling bags is obviated.

While I have herein shown and described one particular embodiment of my invention, I wish it to be understood that I do not confine myself to all the precise details of construction herein set forth by way of illustration, as modification and variation may be made without departing from the spirit of the invention or exceeding the scope of the appended claims.

What I claim is—

1. A device adapted to secure a plurality of fabric pieces together for laundering, comprising a flexible metallic member composed of two sections with a tag having a key way formed thereon connecting the two sections and means for fastening the loose ends of the sections to form a laundry-holding loop.

2. A device adapted to secure a plurality of fabric pieces together for laundry, comprising two chain sections, an identifying tag connecting adjacent ends of the two sections and forming a link in the chain, said tag having a key way thereon adapted to fit on a complementary key bar, and means for fastening the free ends of the chain together to form a laundry-holding loop.

3. A device adapted to secure a plurality of fabric pieces together for laundry, comprising two chain sections, an identification tag connecting the two chain sections and forming an enlarged link between the same, said tag having a key way opening therein, adapted to fit over a complementary key bar, and a safety pin at one free end of the chain adapted to receive a link at the opposite end of the chain to form a laundry-holding loop.

4. A device adapted to secure a plurality of fabric pieces together for laundry, comprising a flexible strand, identifying means having a keyway formed thereon connected to said strand, and means for fastening the loose ends of the strand to form a laundry-holding loop.

Signed at New York city in the county of New York and State of New York this 1st day of October, A. D. 1925.

EDWIN LANE.
